UNITED STATES PATENT OFFICE

165,744

COMBINED HOLDER FOR OYSTERETTES AND SEA FOOD CONDIMENTS

Isidor Fishman, Brooklyn, N. Y.

Application December 29, 1950, Serial No. 13,625

Term of patent 3½ years

(Cl. D44—10)

To all whom it may concern:

Be it known that I, Isidor Fishman, a citizen of the United States, residing at Brooklyn, in the county of Kings and State of New York, have invented a new, original, and ornamental design for a combined Holder for Oysterettes and Sea Food Condiments, of which the following is a specification, reference being had to the accompanying drawing, forming a part thereof.

Fig. 1 is a side elevational view of a combined holder for oysterettes and sea food condiments, showing my new design;

Fig. 2 is an end elevational view;

Fig. 3 is a top plan view; and

Fig. 4 is a sectional view thereof, taken on line 4—4 of Fig. 3;

Fig. 5 is a further sectional view taken on line 5—5 of Fig. 3.

I claim:

The ornamental design for a combined holder for oysterettes and sea food condiments, substantially as shown.

ISIDOR FISHMAN.
